UNITED STATES PATENT OFFICE

ERNEST M. FULLERTON, OF STOUGHTON, MASSACHUSETTS

LAST THIMBLE AND METHOD OF MAKING SAME

Application filed June 5, 1928. Serial No. 283,061.

My present invention relates to thimbles for use in lasts which are utilized in the manufacture of boots and shoes, and includes a novel method of manufacturing such thimbles.

My present invention is applicable to existing lasts, and is equally important and valuable in hinge lasts, block lasts, or other types of lasts, and is directed particularly to the thimble construction.

Shoe lasts are necessarily made with a tubular metallic thimble adapted to be fitted in a recess bored in the heel portion. On this thimble the last and the shoe made thereon may be "jacked" during the many and various processes carried out in shoe manufacture. These various operations require that the last be fitted on a jack, said jack having a spindle over which the thimble is fitted. During the successive shoe manufacturing operations, said last and the thimble fitted therein are subjected to great pressure, hammering, tension and the like, and considerable stresses and strains are transmitted through the thimble and the heel portion of the last during such manufacturing operations. Thus, in heel nailing, leveling, sole laying, and other operations, the wood of the last is subjected to strains and stresses which often loosen the thimble from the last. Furthermore, the continual tempering and drying of the shoe leather imparts an alternate moistening and drying action on the wood of the last which of necessity "gives and takes" somewhat in the drying, which still further tends to loosen the thimble from the last. Once the thimble has become loose, it is very apt to drop out when the last and shoe are inverted before application of the same to a jack.

An important object of the present invention, therefore, is the provision of a thimble for shoe lasts which will obviate the above and other prior difficulties.

A further object of the invention resides in the fact that when once driven into the bored recess in the heel portion, my novel thimble becomes substantially an integral part of the last, being immovable, either longitudinally of said recess, or in a rotary di-

rection. My novel thimble, therefore, when once inserted, will remain in the last recess as long as the last is being utilized, with no likelihood of dropping out or becoming loose.

A further object of the invention is to provide a last thimble which will be economical to manufacture, simple to make, will be simple of application to a last, will be strong, rugged and sturdy, and possessed of long life because of these several advantages.

My present novel last thimble will also act as a reinforcing and strengthening element for the heel portion of a last, which feature is of great advantage where thin cones are utilized on the lasts.

The above and other objects of the present invention, details of construction and advantages, will be hereinafter more fully pointed out, described and claimed.

Referring to the drawings, illustrating preferred embodiments of my invention,

Fig. 1 is a side elevation of my novel thimble at one stage of manufacture;

Fig. 2 is a sectional side elevation illustrating one method of forming the flange on the open end of the thimble;

Fig. 3 is a perspective view of the completed thimble manufactured in accordance with my present invention;

Fig. 4 is a cross-sectional view of the heel portion of a last illustrating my novel thimble in position, said thimble being also shown in cross-section;

Fig. 5 is a perspective view of a modified form of thimble;

Fig. 6 is a perspective view of a still further modification;

Fig. 7 is a perspective view of another modification; and

Fig. 8 is a perspective view of a further form of last thimble constructed according to my invention.

Referring now to the drawings, for a particular description of the invention, and the method of its manufacture, I preferably form my novel thimble from solid stock, drilling or boring, in the thimble 1, a recess 2 adapted to fit over the spindle of a last jack. In the form illustrated in Figs. 1 to 4 inclusive, I

form, on the open end of the thimble, a toothed portion 3 of greater diameter than the rest of the thimble, as clearly illustrated. In the preferred form of my novel thimble, 5 I then form a flange 4 around the open end of the thimble, this flange being formed in any desirable way, as by a swaging tool 5. Due to the fact that the toothed portion 3 is carried completely to the open end of the thimble, when the flange 4 is formed or turned over, it will have a toothed portion 6 on its underside. Thus my novel thimble will be provided with the two angularly disposed toothed surfaces or portions 3 and 6. Therefore, 10 when my novel thimble is driven into the recess 7 in the heel portion of a last 8, the toothed portion 3 will fasten itself very securely into the wood of the last while at the same time the toothed surface 6 on the underside of the flange 4 will firmly grip the wood, 15 leather, or fiber top of the last adjacent to the recess 7. The thimble will thus be permanently affixed to the last, the toothed portions 3 and 6 being firmly embedded and 20 meshed with the wood of the last.

I can form the toothed portion 3 at any desired moment during the process of manufacture, either simultaneously with the drilling of the recess 2, or thereafter.

30 My present novel thimble presents many advantages over existing types of last thimbles, many of which require driving operations of such a nature as to split or injure the last. Although my novel thimble is simpler 35 to apply to the last 8, its holding qualities when once inserted in the recess 7 will be far superior to those of existing last thimbles.

40 Figs. 5, 6, 7 and 8 illustrate slight modifications of my invention of last thimbles, Fig. 5 illustrating a thimble 9 having an enlarged toothed portion 10 adjacent to the open end thereof. This thimble 9 is a straight thimble and is manufactured without any 45 flange, this type of thimble being desirable in some forms of lasts. In Fig. 6 the thimble 11 has an enlarged toothed portion 12 approximately midway of its ends, and in Fig. 7 the thimble 13 has an enlarged tooth portion 14 at its open end, and another enlarged toothed portion 15 at its closed end. Each 50 of these forms of the invention is within the scope of my present invention, and their advantages will be instantly apparent to those skilled in this art.

55 In Fig. 8 I have illustrated another modification of thimble, wherein the thimble 16 has a flange 17 around its open end, the underside 18 of this flange being smooth, or 60 plain, while an enlarged toothed portion 19 is formed on the body of the thimble 16 closely adjacent to the flange 17. This type of thimble will also be found to be very advantageous in many forms of lasts, and is also 65 within the range of my present invention.

I believe that my last thimbles, as illustrated in the present application, are novel, as well as the process of manufacturing same, and I have therefore claimed the same broadly herein.

70 While I have necessarily described my present invention somewhat in detail, it will be appreciated that I may vary the size, shape and arrangement of parts within reasonably wide limits without departing from the spirit 75 of the invention.

My invention is further described and defined in the form of claims as follows:

1. That improvement in the art of manufacturing last thimbles which consists in 80 drilling, in a bar of solid stock, a recess of predetermined depth, then providing, on the outer surface of said thimble, a toothed portion of greater diameter than the rest of said thimble.

2. That improvement in the art of manufacturing last thimbles which consists in 85 drilling, in a bar of solid stock, a recess of predetermined depth, then providing, on the outer surface of said thimble, and adjacent 90 to the open end thereof, a toothed portion of greater diameter than the rest of said thimble, and then swaging the open end of said thimble to provide a flange substantially perpendicular to the outer walls of 95 said thimble, whereby the underside of said flange will be provided with a plurality of projecting teeth.

3. That improvement in the art of manufacturing last thimbles which consists in 100 drilling, in a bar of solid stock, a recess of predetermined depth, then providing, on the outer surface of said thimble, and adjacent 105 to the open end thereof, a toothed portion of greater diameter than the rest of said thimble, and then swaging the open end of 110 said thimble to provide a flange substantially perpendicular to the outer walls of said thimble, whereby the underside of said flange will be provided with a plurality of projecting teeth and the surface of said thimble closely 115 adjacent to said flange will also be provided with a plurality of projecting teeth.

4. As an article of manufacture, a last 120 thimble, and a toothed surface substantially encircling said thimble throughout a predetermined distance, said toothed surface being normally of greater diameter than the rest of said thimble and adapted to mesh with and grip the wood of a last when driven 125 therein.

5. As an article of manufacture, a last 130 thimble, a flange around the open end of said thimble, a plurality of projecting teeth on the under side of said flange, and a plurality of teeth substantially encircling said thimble for a predetermined distance closely adjacent to said flange.

6. As an article of manufacture, a last thimble, and a plurality of toothed surfaces 135

on said thimble, said toothed surfaces being disposed at angles relatively to each other, one of said toothed portions being normally of greater diameter than the body of said thimble.

5 7. That improvement in the art of manufacturing last thimbles, which consists in drilling, in a bar of solid stock, a recess of predetermined depth, then providing on the outer surface of said thimble, a toothed portion of greater diameter than the rest of said thimble, and then swaging the open end of said thimble to provide a flange substantially perpendicular to the outer walls of said thimble.

10 15 In testimony whereof, I have signed my name to this specification.

ERNEST M. FULLERTON.
